UNITED STATES PATENT OFFICE.

DALLAS DU BOIS, OF MONTCLAIR, NEW JERSEY.

DESIGN FOR A GAME-BOARD.

SPECIFICATION forming part of Design No. 28,049, dated December 14, 1897.

Application filed October 26, 1897. Serial No. 656,471. Term of patent 3½ years.

To all whom it may concern:

Be it known that I, DALLAS DU BOIS, a citizen of the United States, residing at Montclair, in the county of Essex and State of New Jersey, have invented and produced a new and original Design for a Game-Board, of which the following is a specification, reference being had to the accompanying drawings, forming a part thereof, in which—
5 Figure 1 is a plan view of the game-board, and Fig. 2 is a vertical section on the line 2 2 of Fig. 1.

10 The leading feature of the design consists in a board A, provided with a central turn-

table B, having marginal pockets C, and partitions D, radiating from the space in which the turn-table is placed.

15 A minor feature of the design consists in a checkered formation E on the upper face of the board and a marginal flange F for the board.

20 I claim—

The design for a game-board herein shown and described.

DALLAS DU BOIS.
